UNITED STATES PATENT OFFICE.

JOSE RAMOS POWER, OF MALAGA, SPAIN.

APPARATUS FOR PREVENTING FERMENTATION.

SPECIFICATION forming part of Letter's Patent No. 513,199, dated January 23, 1894.

Application filed March 3, 1893. Serial No. 464,631. (No model.) Patented in Spain July 18, 1892, No. 13,462.

To all whom it may concern:

Be it known that I, JOSE RAMOS POWER, a subject of the King of Spain, residing at Malaga, Spain, have invented certain new and 5 useful Improvements in Apparatus for Preventing the Fermentation of Wort, Wines, and other Liquids by Fumigating the Same with Pure Sulphur, of which the following is a specification.

10 Patent has been taken out in Spain, No. 13,462, dated July 18, 1892.

It is the object of my invention to provide a simple and effective apparatus for subjecting wines, wort and other liquids to the fumes 15 of sulphur or the like said apparatus being constructed and arranged to continue the fumigation for any desired length of time, the wine or other liquid falling in a divided condition or spray while the fumes of the sulphur rise and fumigate the falling spray effectively. This treatment of the wine or 20 other liquid will prevent the same from fermenting.

The apparatus is shown in the accompanying drawings, in which—

Figure 1, is a perspective view of the apparatus complete, and Fig. 2, a sectional view of the furnace and the spraying vat supported thereby.

25 The apparatus includes essentially two or more vats A, B, which as shown may be made of masonry below the level of the ground or floor, a furnace brickwork N adjacent to the vats; a furnace K within said brickwork; a fumigating pot L connected by a pipe M to the lower part of the vat I in which is arranged a series of horizontal partitions N' perforated to divide the liquid as it falls from the top of the vat, where it is introduced 30 through a pipe G, leading from a pump F, Fig. 1, arranged alongside the furnace wall. The apparatus also includes the horizontal pipe E, extending over the receiving vats, A, B, and having the depending suction pipes 45 A', B' provided with cocks C, D, said pipe E, being connected with the suction end of the suction and force pump F.

The hearth or furnace above referred to is opened at its lower part and through its ash 50 box a draft of natural air is permitted which keeps alive the sulphur flame, said sulphur being placed, either in lumps or pulverized,

in an iron or earthenware movable plate P resting on a fixed grate provided for this purpose in said furnace. These vapors or fumes 55 of pure sulphur are carried up to be introduced in the vat, as described, said vat being provided with fourteen or more of the boards perforated at short intervals, through which the wort or liquids descend or flow down, like 60 rain, from one to another, the first or upper board being provided with a piece of thick loosely woven linen through which the wort passes and which serves, in the first place to take off from said wort the thick particles it 65 may contain, and, secondly, to prevent the rapid escape of the sulphur fumes.

The operation is as follows:—When the fountain A (Fig. 1) is filled with wort, the cock C is opened, and the cock D remains 70 closed, and as the pump is operated the liquid passes through the pipe E into the pump body F and is discharged through the pipe G, and then it is emptied into the piece of linen H, and as it flows from board to board it descends slowly through the sulphur fumes or 75 vapors and becomes impregnated with the same, and as it reaches the lower part of the vat is readily discharged through the rubber pipe J, by which it is carried to the empty receptacle B. As before explained, the natural air draft through the bottom of the furnace, 80 takes place at the point K.

As has already been explained, supposing the fountain A to be filled with wort, the 85 pump is operated until said fountain becomes empty and the fountain B will be filled it being fumigated with sulphur once, but since one fumigation with sulphur is not sufficient in order to prevent fermentation, a 90 second fumigation may be effected as desired, by simply closing the cock C, opening the cock D and by transferring the lower end of the rubber pipe J to the fountain A and thus the pump will go on operating until it fills 95 again the fountain A, whereby the wort, wine or any other liquid which may be under treatment is fumigated twice with sulphur and the operation may be repeated until the required degree or quantity of sulphur is applied to the liquid.

100 Any suitable form of pump may be used, and if desired the liquid may be introduced into the top of the spraying vat in any other

desired way as by hand and instead of the series of perforated partitions for spraying the liquid any other suitable means may be used.

The receiving vats may be of different form 5 and arrangement from those shown.

I claim—

In combination, the elevated spraying tank, the brickwork for supporting the same, the furnace arranged within the brickwork, the 10 pipe M leading up from the furnace into the lower part of the spraying tank, the two vats A, B, arranged below the spraying tank, the loose pipe J extending from the lower end of the spraying tank and adapted to be transferred from one vat to the other, the force 15 pump having a pipe connecting with the upper

part of the spraying tank, the cross pipe E extending over the two vats A, B, and having branches A', B' depending therein and provided with valves, the said pipe E being connected with the force pump whereby the liquid may be drawn from either vat while the pipe J may be transferred to deliver the liquid by gravity into the other vat, substantially as described. 20 25

In witness whereof I have hereunto set my hand in presence of two witnesses.

JOSÉ RAMOS POWER.
